United States Patent Office

Des. 200,861
Patented Apr. 13, 1965

200,861

DOLL

Joseph J. Spano, 475 Niagara St., Buffalo, N.Y.

Filed Dec. 17, 1964, Ser. No. 83,068

Term of patent 14 years

(Cl. D34—4)

Fig. 3.

FIG. 1 is a front elevational view of a doll embodying my new design;

FIG. 2 is a side elevational view taken from the right of FIG. 1;

FIG. 3 is a bottom plan view;

FIG. 4 is a side elevational view taken from the left of FIG. 1;

FIG. 5 is a rear elevational view; and

FIG. 6 is a top plan view.

I claim:

The ornamental design for a doll, substantially as shown.
